FIG. I.

FIG. II.

FIG III.

FIG. IV

INVENTOR:

THOMSON KING,

by Arthur E. Page
Attorney.

UNITED STATES PATENT OFFICE

THOMSON KING, OF POTTSTOWN, PENNSYLVANIA, ASSIGNOR TO THE PEERLESS HEATER COMPANY, OF BOYERTOWN, PENNSYLVANIA, A CORPORATION OF PENNSYLVANIA

WATER HEATER

Application filed August 15, 1928. Serial No. 299,653.

My invention relates to heaters comprising a series of similar unit sections adapted to be connected in varying numbers in accordance with the desired capacity of the heater; and particularly to such heaters wherein each section is provided with an individual gas burner; so that each of said sections is, to that extent, independent of the others, and economy of operation is attainable by rendering more or less of said section burners operative and inoperative in accordance with variable seasonal requirements.

As hereinafter described, my invention includes features of construction and arrangement of a heater section which is formed of a single casting and which facilitate the circulation of water therein.

My invention includes the various novel features of construction and arrangement hereinafter more definitely specified.

In said drawings; Fig. I is a vertical side edge view of a single metal casting forming a unitary heater section embodying my improvements.

Fig. II is an elevation of the right hand side of said section, as shown in Fig. I.

Fig. III is a fragmentary plan sectional view, taken on the line III, III in Fig. II.

Fig. IV is a fragmentary sectional view, taken on the line IV, IV in Fig. II.

In said figures; the heater section 1 is a single casting of metal, of inverted U-shape, having opposite parallel plane surfaces 2, 2 with spacing ribs 3 extending outwardly therefrom adapted to contact with similar spacing ribs upon adjoining sections to facilitate the assembling of said sections, shaped as shown in Figs. I to IV inclusive, in parallel relation; said ribs serving to retain between them any suitable cement by which the joints between said sections may be sealed.

Said casting 1 comprises two outer vertically pendent water leg conduits 4, at opposite edges thereof; the lower ends of said legs being closer together than the upper ends thereof, but said section being wider at the bottom than at the top.

The upper ends of said pendent leg conduits 4 are connected by the two horizontal water conduits 5 and 6, respectively at the

top, and intermediate of the height, of said section. Said intermediate section 6 forms the top wall of the combustion chamber or "fire-box" 7, the opposite side walls of which are formed by said leg conduits 4. Said top section 5 and intermediate section 6 are connected by two inner vertical water conduits 8, parallel with and spaced between said outer vertical conduits 3 and 4. Said inner conduits 8 are shorter at their outer sides 9 than at their inner sides 10 so that the water space in said section is of greater cross sectional area at its upper corners 12 than elsewhere; which facilitates the circulation of water as hereinafter described.

Said outer conduits 4 are connected with said intermediate horizontal conduit 6 by two oppositely counterpart oblique water conduits 14, respectively extending inwardly between said outer conduits obliquely upward from the latter and merging into said intermediate conduit 6 respectively in alignment with said inner vertical conduits 8 so that direct water passageways are formed from the lower ends of said oblique conduits 14 to the top of the heater section 1 and respectively leading into the large corner spaces 12, from which the water is re-circulated downwardly in the outer conduits 4 by the forcible upflow of water from said oblique conduits 14.

The forcible upflow of the water from the leg conduits 4 thru the oblique conduits 14 and superimposed conduits 8 is induced not only by the fact that said oblique conduits 14 are of small cross sectional area and overhang the burner 19 or other source of heat, but also due to the provision on each of said conduits 14 of a series of transversely extending annular outwardly projecting ribs 21 which are preferably outwardly tapered and form a series of passageways 22 between them for the products of combustion escaping from the chamber 7 into the flues 15. By such construction, the surface of said conduits 14, exposed to the heat, is very much greater in proportion to the volume of water in said conduits 14 than in any other portion of said heater section; thus causing the water in said conduits 14 to be heated to a higher degree than in any other portion of the section and

thus inducing rapid upward currents of the water, directly, vertically, thru said conduits 14 and 8 and thus effecting the maximum rapidity of re-circulation of the water from 5 and to said pendent legs 4 which is attainable in such a section. Moreover, the surfaces of all of said conduits 4, 5, 6 and 8 which are exposed to the products of combustion in the fire-box 7 and flues 15, 16 and 17 is very much 10 augmented, for a given dimension of the section, transverse to its plane, by forming each of said conduits as a hexagonal prism, as exemplified in Figs. III and IV, with double plane sides in angular relation presented inwardly toward the source of heat, instead of flat surfaces at right angles to the general plane of the section, as in the prior art. Of course, such angular faces present a greater 15 heat absorbing area than if such conduits had 20 but a single plane face extending transversely to the general plane of the section. However, both the outer and inner surfaces of said oblique conduits 14 are curved, as indicated in Figs. II and III, to facilitate the 25 passage of water thru them and the circulation of the products of combustion around them thru said passageways 22.

Each such section 1 has a plurality of water ports upon opposite sides thereof, forming 30 transverse passageways for circulation of water between adjoining sections; thru push nipples 24; such ports being exemplified at 25, at the lower ends of said vertical leg conduits 4 and at 26, at the middle of said top 35 conduit 5. The respective ports 25 and 26 have individual annular flanges 28 and 29 surrounding the same in spaced relation therewith, as indicated in Fig. II, and extending outwardly from the opposite plane surfaces 40 of said section to the same extent as the spacing ribs 3, as indicated in Fig. I. Said port flanges are adapted for connection with means for sealing said sections in smoke-tight 45 relation at said ports. Such means may include suitable cement which is held, in annular form, within and between the adjoining port flanges, as indicated at 30 in Figs. I and II.

In order to conduct the hot water from such 50 a heater to the radiating means of the heating system connected therewith; I provide the section 1 with a hot water discharge neck 31 at the top thereof, intermediate of its width and in communication with the transversely 55 extending ports 26. Such construction and arrangement, in unitary relation with the section, avoids the cost and trouble of providing and connecting a separate manifold with the respective heater sections.

60 In order to maintain a series of such sections 1 assembled in coupled relation, as above contemplated, I find it convenient to provide each section with a plurality of bolt flanges 32 with apertures 34 for bolts 35, 65 which are provided with nuts, etc., for re-

taining them in assembled relation. As indicated in Fig. II; two of said bolt flanges 32 are at the top of the section immediately adjoining said neck 31 and serve to brace the latter in connection with the top wall of the section; and two of said flanges are respectively at the outer edges of the lower portions of said leg conduits 4, where they brace the outwardly extending port portions of said conduits 4 in connection with the outer walls of the latter.

The lower ends of said legs 4 are conveniently arranged closer together than the upper ends thereof, to afford an upwardly increasing area for the fire-box 7; the upper space therein, for the products of combustion, being wider than the fuel space at the bottom thereof and thus allowing for the increase in volume of the fuel incident to its combustion. However, said section 1 is, nevertheless, wider at its bottom than at its top and thus affords a very stable construction and arrangement to resist such lateral stresses as may be imposed upon it by expansion and contraction of the heat radiating system aforesaid connected with the discharge neck 31.

However, I do not wish to limit myself to unitary heater sections each having all of the features of improvement aforesaid, as it is obvious that various modifications may be made therein without departing from the essential features of my invention, as defined in the appended claims. For instance, the heat absorbing ribs may be alike on both the 100 oblique, sigmoidally curved, conduits 14, i. e., either all horizontal or all in planes which are radial with respect to the centers of curvature of said conduits; the former permitting passage of products of combustion with greater facility, and the latter affording a greater mixing and agitation of said products and retarding their traverse thru the passageways between said ribs and thus affording a greater facility for heat 105 absorption.

I claim:

1. In a heater section, a single casting of inverted U-shape comprising a horizontal water conduit and a pair of depending hollow legs forming conduits communicating with said horizontal conduit, each of said conduits being hexagonal in crosssection, with single plane sides thereof at the opposite plane surfaces of said section, and with double plane sides in angular relation presented inwardly toward the fire-box; whereby the inner faces of said conduits, toward the firebox, have a greater heat absorbing area than if said faces were in a single plane; two oppositely counterpart oblique water conduits, of less diameter than the least diameter of said hexagonal conduits, respectively extending upwardly from said legs to said horizontal conduit, merging into both and forming 130

ing transverse flues between said oblique conduits and the junctions of the other conduits; each of said oblique conduits being curved upon its outer surface and provided with a 5 series of horizontally extending parallel outwardly projecting annular ribs, forming a series of passageways between said ribs leading from the fire-box to said flue; whereby said oblique conduits have a greater heat absorbing effect than the other portions of said 10 section and consequent greater heating effect upon the water therein, and induce a rapid circulation of the water obliquely upward in said section from the outer to the inner portions thereof; inducing a downward circulation 15 in the upper portion of said legs, with maximum water heating efficiency of the section; said section having intermediate vertical conduits, in spaced relation between 20 said outer leg conduits, respectively in alignment with the upper ends of said oblique conduits and extending directly vertically to the water space in the top of said section; said water space, at the top of said section, being 25 of greater area at the corners of said section than elsewhere; whereby the rapid circulation of the water to and from said oblique conduits is facilitated.

2. In a heater section; a single casting of 30 inverted U-shape, having opposite parallel plane surfaces, with spacing ribs projecting outwardly therefrom; said casting comprising two outer vertically pendent water leg conduits at opposite edges thereof, the lower 35 ends of said legs being closer together than the upper ends thereof; and said upper ends being connected by two horizontal water conduits, respectively at the top, and intermediate of the height, of said section; said top 40 and intermediate conduits being connected by two inner vertical water conduits, parallel with, and spaced between, said outer vertical conduits and shorter at their outer edges than at their inner edges; each of said 45 conduits being hexagonal in cross section; said outer conduits being connected with said intermediate horizontal conduit, by two oppositely counterpart oblique water conduits, extending between said outer conduits, obliquely upward from the latter, and respectively merging into said intermediate conduit in alignment with said inner vertical conduits; each of said oblique conduits being 50 curved upon its outer surface and provided with a series of horizontally extending, parallel, outwardly projecting ribs; each of said 55 ribs being outwardly tapered; said section having water ports upon opposite sides thereof respectively at the lower ends of said 60 vertical leg conduits and at the middle of said top conduit; each of said ports having an annular flange, surrounding the same, for connection with means for coupling said section with adjoining, similar, sections; said 65

section having a discharge neck at the middle of its top section, with its axis extending vertically; said section having four bolt flanges with apertures for bolts whereby adjoining sections may be held together; two 70 of said flanges being respectively at the outer edges of the lower portions of said leg conduits, and two of said flanges being respectively at opposite sides of said neck; the apertures thru said flanges having their axes 75 parallel and at right angles to the plane faces of said sections.

In testimony whereof, I have hereunto signed my name at Boyertown, Pennsylvania, this seventeenth day of July, 1928.

THOMSON KING.
